United States Patent Office

Des. 218,879
Patented Oct. 6, 1970

218,879

COMBINED SPOOL OF TYPEWRITER RIBBON AND PACKAGE THEREFOR OR SIMILAR ARTICLE

Delmar J. Lasher, James P. Wang, and Frederick A. Weaver, Lexington, and Finley J. Wills, Winchester, Ky., assignors to International Business Machines Corporation, Armonk, N.Y., a corporation of New York

Filed Feb. 13, 1969, Ser. No. 15,759

Term of patent 14 years

Int. Cl. D9—99

U.S. Cl. D9—192

FIG. 1

FIG. 2

FIG. 4

FIG. 3

FIG. 5

FIG. 6

FIG. 7

FIG. 1 is a perspective view of a combined spool of typewriter ribbon and package therefor or similar article, showing our new design;

FIG. 2 is a top plan view on a larger scale;

FIG. 3 is a front elevational view thereof;

FIG. 4 is a left side elevational view thereof;

FIG. 5 is a right side elevational view thereof;

FIG. 6 is a bottom plan view thereof; and

FIG. 7 is a rear elevational view thereof.

We claim:

The ornamental design for a combined spool of typewriter ribbon and package therefor or similar article, substantially as shown.
